Attys.

UNITED STATES PATENT OFFICE.

CARL E. JOHNSON, OF CHICAGO, ILLINOIS.

BAFFLE PLATE FOR BOILER FIRE BOXES.

Application filed October 16, 1924. Serial No. 743,863.

This invention relates to improvements in boiler fire boxes and is more particularly directed to improvements in baffle plate construction for boiler fire boxes.

5 The principal object of the invention is to provide an improved baffle plate construction for boiler fire boxes which can be moved with respect to the flues of the boiler without any great effort so that easy access 10 to the flues may be had for cleaning them.

A further object of the invention is to provide a generally improved construction 15 of boiler fire box baffle plate in the form of a deflecting wall which completely covers the forward end of the flues adjacent the flue sheet of the boiler and at the same time provides an outlet for unburned gases to be directed vertically downward through the baffle plates where it passes adjacent the 20 bottom of the baffle plates into the flame of fire coming up from below the baffle plates.

A still further object of the invention is to provide an improved pivoted baffle plate 25 for a boiler fire box which is provided with the usual arched construction that will permit the baffle plate to swing from its normal operative position to a position where the baffle plates are swung about their pivots parallel to the sides of the fire box without 30 the necessity of removing any parts from the fire box so that easy access to the flues for cleaning can be readily had.

A further object of the invention is to provide an improved baffle plate construction 35 which will materially enhance the commingling and ad-mixing of the fire box gases for the purpose of producing substantially perfect combustion in the fire box.

These and other objects are accomplished 40 by providing a construction and an arrangement of the various parts in the manner hereinafter described and particularly pointed out in the appended claims.

The invention in the present instance is 45 an improvement over my copending application Serial No. 735,099 filed August 30, 1924.

Referring to the drawings Fig. 1 is a 50 cross sectional view taken on a vertical plane passing through substantially the longitudinal center of the boiler fire box.

Fig. 2 is a cross sectional view of the 55 boiler fire box taken on the line 2—2 of Fig. 1, looking in the direction indicated by the

arrows showing my improved baffle plates 55 mounted therein.

Fig. 3 is a detail cross sectional view taken on the lines 3—3 in Fig. 2.

Fig. 4 is a perspective front elevational view showing the manner in which my improved pivoted baffle plates may be swung to the position in which easy access to the flues of the boilers may be readily had, and

Fig. 5 is an enlarged detail cross sectional view showing the construction of the hinges 65 of the baffle plates.

In connection with the efficient operation of a boiler it is essential at regular intervals to clean the flues of the boiler and where refractory baffles or deflecting walls are permanently built in the fire box adjacent the flues of fire brick it is necessary in order to have access to the flues to completely knock down the fire brick and rebuild the deflecting wall on each occasion that the flues are cleaned. This method entails considerable expense in time and labor and each time it is necessary to completely extinguish the fire in the fire box in order that the brick wall may be removed from the fire box.

In the present invention I have overcome these difficulties by providing a construction of hinged baffle plates which are pivoted adjacent the side walls of the fire box and are adapted to swing from the center toward the sides of the fire box without the necessity of entering the fire box or removing any parts therefrom so that easy access to the flues for cleaning may be readily had, and in addition thereto I have provided a construction in which passages are provided in the baffle plates for conducting the unburned combustible gases which accumulate in the top of the fire box and direct them into the flame of the fire adjacent the bottom of the baffle plates.

In carrying out my invention I have shown the same in connection with a boiler 10 provided with the usual wall or sheet 11 and fire box as shown at 12. The fire box 12 is provided with the usual arched top or dome 13 and vertically extending side walls 14. Secured to the front end of the sheet 11 of the boiler 10 in a manner well known in the art is a front sheet 15. Secured to the front end of the walls 13 and 14 of the fire box 12 and contacting with

the front sheet 15 is a front forward fire box wall 16. The fire box wall 16 and the front wall 15 of the boiler are provided with a common opening 17 extending into the 5 fire box through which the fuel is supplied to the boiler. Mounted in the rear end of the fire box 12 in a manner well known in the art is the usual flue sheet or partition wall 18. Secured in the flue sheet 18 at 10 regular intervals are the usual flues 19 which extend into the boiler proper. Mounted in the bottom of the fire box 12 is the usual grate 20 of any well known construction. The above described boiler 15 has been selected for the purpose of illustrating my invention, it being the conventional form of boiler now in use.

The essential feature of my invention is the provision of two improved baffle plates 20 21 and 22 which are pivoted on brackets 23 which are secured to the side walls 14 on the opposite sides of the fire box 12 by means of bolts 24. The baffle plates are 25 preferably secured to the brackets 23 by pins 25. The baffle plates are preferably made of cast metal and are provided with vertically extending ribs 26 and horizontal ribs 27 which are formed integrally with the baffle plates. The upper portion of each 30 of the baffle plates are curved inwardly as shown at 28 and the innermost portion, as shown at 29, is adapted to contact with the vertical portion of the flue sheet 18. The upper ends 29 of the curved portions 28 of 35 the baffle plates are preferably curved to conform with the arch shaped top 13 of the fire box 12 and are arranged so as to form a space 30 between the curved end 29 of the baffle plate and the arch shaped top 13 40 of the fire box, as shown in Fig. 2, so that when the baffle plates are swung to their opened or inoperative position or to the position in which access to the flues for 45 cleaning may be readily had, there will be sufficient clearance between the top of the baffle plates and the arch shaped top 13 of the fire box to permit this swinging movement, as shown in Fig. 4. One of the baffle plates 21 is preferably provided with a 50 laterally projecting overlapping flange 31 which is adapted to form a stop for aligning the opposite baffle plate 22 with respect to the baffle plate 21 when they are in their normal operative position or the position 55 shown in Fig. 2.

Another essential feature of my improved baffle plate construction is the provision of passageways 32 extending vertically through the baffle plates adjacent their inner edges 60 through which the gases which accumulate in the upper part of the fire box enter at points 33 adjacent the curved portions 28 of the baffle plates and pass vertically downwardly through exits 34 adjacent the 65 lower end of the baffle plates. These con-

duits are preferably formed in the baffle plates by positioning cores in the molds when the baffle plates are being molded. By this arrangement it will be seen that when the hot coals and fuel of the fire are 70 built up to their normal position where they reach a point relatively above the lower end of the baffle plates, the baffle plates form a deflecting wall completely baffling the 75 flues from the fire box by reason of the curved portions 28 of the baffle plates contacting with the vertical portion of the flue sheet 18 and it will be further noted that all unburned combustible gases accumulating in the upper part of the fire box will 80 be directed through the passageway 32 in each of the baffle plates in a direction indicated by the arrows in Fig. 1. These gases will then be discharged through the opening 34 adjacent the lower end of the baffle 85 plates where they will come in contact with the intense heat of the fire box and be consumed in the flame.

From the above description it will be seen that I have provided an improved 90 baffle plate construction for a boiler fire box in which access to the flues of the boiler may be readily had by simply engaging the inner or free ends of the baffle plates and swinging them about their respective pivots from 95 the position shown in Fig. 2 to the position shown in Fig. 4 without the necessity of extinguishing the fire in the fire box.

It will be noted that by my improved 100 curved construction which is formed integrally with the top of each of the baffle plates I have provided a construction which will completely baffle the fire box from the flue regardless of the curved or domed construction of the fire box and at the same time 105 this particular construction permits these baffle plates to swing outwardly without interfering with or striking the top of the fire box.

While in the above specification I have 110 described one embodiment which my invention may assume in practice, it will of course be understood that the same is capable of modification and that modification may be made without departing from the spirit and scope of the invention as expressed in the 115 following claims.

What I claim as my invention and desire to secure by Letters Patent is:

1. In combination with a boiler, of a fire box therefor having an arch-shaped top, a 120 plurality of flues extending from said fire box through said boiler, a plurality of baffle plates pivoted to the side walls of said fire box for baffling said fire box from said flues and means formed on the top of said baffle plates and conforming to the arch-shaped top of said fire box whereby said baffle plates 125 may be swung to a position parallel with the sides of said fire boxes.

2. In combination with a boiler, of a fire 130

box therefor having an arch-shaped top, a plurality of flues extending from said fire box through said boiler, a plurality of baffle plates pivoted to the side walls of said fire box and 5 extending into said arch-shaped top for baffling said fire box from said flues and means formed on the top of said baffle plates and conforming to the arch-shaped top of said fire box whereby said baffle plates may be 10 swung to a position parallel with the sides of said fire box.

3. In combination with a boiler, of a fire box therefor, a flue sheet forming a partition wall between said fire box and said 15 boiler, flues extending from said flue sheet through said boiler, a baffle plate pivoted to the wall of said fire box and spaced from said flue sheet for baffling the fire box from said flues and a curved portion formed integral- 20 ly with said baffle plate and conforming to the curvature of said arch-shaped top whereby said baffle plate may be swung unob- structively on its pivot.

4. In combination with a boiler, of a fire 25 box therefor having an arch-shaped top, a flue sheet forming a partition wall between said fire box and said boiler, flues extending from said flue sheet through said boiler, a plurality of baffle plates pivoted to the wall 30 of said fire box and spaced from said flue sheet for baffling the fire box from said flues and means formed on the top of said baffle plates and conforming to the arch-shaped top of said fire box whereby said baffle plates 35 may be swung to a position parallel with the sides of said fire box.

5. In combination with a boiler, of a fire 40 box therefor, a flue sheet forming a partition wall between said fire box and said boiler, flues extending from said flue sheet through said boiler, and a plurality of baffle plates pivoted to the walls of said fire box and spaced from said flue sheet, each of said baffle plates having upper portions adapted 45 to contact with said flue sheet for completely baffling said fire box from said flues.

6. In combination with a boiler, of a fire 50 box therefor, a flue sheet forming a partition wall between said fire box and said boiler, flues extending from said flue sheet through said boiler, and a plurality of baffle plates pivoted to the walls of said fire box and spaced from said flue sheet, each of said baffle plates having curved upper portions adapted to contact with said flue sheet for completely baffling said fire box from 55 said flues.

7. In combination with a boiler, of a fire 60 box therefor, a flue sheet forming a partition wall between said fire box and said boiler, an arch-shaped sheet forming the top of said fire box, flues extending from said flue sheet through said boiler, and a plurality of pivoted baffle plates mounted in 65 said fire box and having curved portions

extending into said arch-shaped top in a manner whereby said baffle plates may be swung from a position completely baffling said flues to a position where easy access to said flues may be readily had.

70

8. In combination with a boiler, of a fire box therefor, a flue sheet forming a partition wall between said fire box and said boiler, an arch-shaped sheet forming the top of said fire box, flues extending from said flue sheet through said boiler, and a plurality of baffle plates pivoted to the opposite sides of said fire box and having upwardly extending portions thereof extending into said arch-shaped top, each of said baffle 75 plates being so constructed as to completely baffle the fire box from said boiler when in their normally closed position and to permit easy access to the flues when in their opened position.

85

9. In combination with a boiler, of a fire box therefor, a flue sheet forming a partition wall between said fire box and said boiler, an arch-shaped sheet forming the top of said fire box, flues extending from said flue sheet through said boiler, and two baffle plates pivoted on the opposite sides of said fire box, each of said baffle plates having upper portions adapted to contact with said flue sheet and spaced from said arched top 90 when in their normally closed position.

95

10. In combination with a boiler, of a fire box therefor, a flue sheet forming a partition between said fire box and said boiler, an arch-shaped sheet forming the top of said fire box, flues extending from said flue sheet through said boiler, pivoted baffle plates mounted in said fire box, and means formed integrally with and extending out of the plane of said baffle plates and into 100 said arch-shaped top whereby said baffle plates may be swung from a position completely baffling said fire box from said boiler to a position where the baffle plates extend parallel to the sides of said fire box.

110

11. In combination with a boiler, of a fire box therefor, a flue sheet forming a partition between said fire box and said boiler, an arch-shaped sheet forming the top of said fire box, flues extending from said flue sheet through said boiler, pivoted baffle plates mounted in said fire box, and curved upper portions formed integrally with said baffle plates whereby said baffle plates may be swung from a position completely baffling 115 said fire box from said boiler to a position where the baffle plates extend parallel to the sides of said fire box.

120

12. In combination with a boiler, of a fire box therefor, having an arch-shaped top, a flue sheet forming a partition between said fire box and said boiler, flues extending from said flue sheet through said boiler, baffle plates pivotally mounted on the opposite sides of said fire box, upwardly extending 125 130

portions formed integrally with said baffle plates and extending into the arch-shaped top of said fire box so that when the baffle plates are in their normal operative position the upper portion of said fire box is completely baffled from said flues, and to permit the baffle plates to be swung on the

pivot unobstructively to a position in which the baffle plates extend parallel to the sides of said fire box.

10

In testimony whereof I have signed my name to this specification, on this 13th day of October, A. D. 1924.

CARL E. JOHNSON.
